UNITED STATES PATENT OFFICE.

LUI C. VERGANO, OF BERKELEY, CALIFORNIA.

WINDMILL GOVERNOR.

Application filed January 21, 1922. Serial No. 530,983.

To all whom it may concern:

Be it known that I, LUI C. VERGANO, a subject of the King of Italy, residing at Berkeley, in the county of Alameda and 5 State of California, have invented certain new and useful Improvements in Windmill Governors; and I do hereby declare the following to be a full, clear, and exact description of the invention, such as will enable 10 others skilled in the art to which it appertains to make and use the same.

This invention has relation to windmills and more particularly to the governing mechanism whereby the same is thrown into 15 or out of the wind, as required and according to the nature of the work to be performed.

The invention provides a governor mechanism for windmills, which is wholly automatic in action in throwing the engine into or out of the wind and which requires no attention on part of the user, after the same has been properly adjusted, except that required for oiling and repairs.

Other objects and advantages will be apparent and suggest themselves as the nature of the invention is understood.

While the drawings illustrate an embodiment of the invention it is to be understood, 30 that in adapting the same to meet different conditions and requirements, various changes in the form, proportion and minor details of construction may be resorted to without departing from the nature of the invention.

Referring to the accompanying drawings forming a part of the application,

Figure 1 is a detail view of a windmill governor mechanism embodying the invention, showing the relation of the parts when 40 the windmill is inactive or out of the wind,

Figure 2 is a view similar to Figure 1, showing the relationship of the parts when the windmill is in action or thrown into the wind,

Figure 3 is a view similar to Figures 1 and 2, with the windmill partly thrown into the wind, the rudder arm occupying a position intermediate its extreme movements,

Figure 4 is a detail view of a portion of a tank, the float therein and connecting means whereby to automatically trip the governor mechanism to prevent the overflow or the running dry of the tank,

Figure 5 is a detail view of the dogs which cooperate with the rudder arm to secure

the same and the reversing trip coating with said dogs, and

Figure 6 is an edge view of the parts shown in Figure 5, the springs cooperating therewith being omitted.

Corresponding and like parts are referred to in the following description and designated in the several views of the drawings by like reference characters.

The numeral 15 designates the head of a windmill, which may be of any construction, depending upon the make of the engine adapted to be equipped with the governor mechanism. The numeral 16 designates the rudder arm which is pivoted to the head 15 in any well known manner and which carries the tail vane which holds the windmill either in or out of the wind, according to its relative position. Arms 17 and 18 are disposed relatively at a right angle to each other and spring outwardly from the head 15. A curved bar 19 is attached to the arms 17 and 18 and its inner edge is provided with teeth 20. The toothed bar 19 is disposed concentric with the axis of the rudder arm 16. An arcuate bar 21 is mounted on the toothed bar 19 and has a limited circumferential movement relative to the bar. Slots 22, formed in the bar 21, receive screws 23, or like parts, carried by the bar 19, whereby to hold the bar 21 in place and limit its movement relative to the bar 19.

Pins 12 and 13 are provided at opposite end of the arcuate bar 21 and constitute stops, whereby to trip the mechanism to effect release of the rudder arm when a reversing thereof becomes necessary. A contractile helical spring 24 connects a projection 25 of the bar 21 with a projection 26 of the bar 19 and normally holds the bar 21 at the limit of its movement in one direction.

The bar 21 is moved in the opposite direction against the tension of the spring 24 by means of a float 27 arranged to operate in a tank 28 and moved vertically by the change of level of the water in the tank.

A lever 28 is pivoted near one end to a bracket 29 or other convenient support and the stem 30 of the float 27 has adjustable connection therewith. A flexible connection 31, such as a cable, is connected at one end to the bar 21 and its opposite end is connected to the short arm of the lever 28, a swivel joint 32 being in the length of the connection to prevent twisting thereof incident to the pivotal movement of the wind-

mill head 15. The flexible connection 31 passes around guide pulleys 33 and 34, the guide pulley 33 being at the outer end of the arm 17 and the guide pulley 34 being mounted upon the head 15 with its inner side in line with the opening of the head in coincident relation with the axis thereof, whereby to give proper direction to the vertical portion of the connection 31. When the float 27 rises with the level of the water in the tank 28, the connection 31 is pulled upon, thereby moving the bar 21 against the tension of the spring 24, and when the float descends, the connection 31 is relaxed, thereby permitting the spring 24 to come into play to move the bar 21 in an opposite direction. Advantage is taken of the movements of the bar 21 to effect release of the rudder arm 16 at either extreme movement, whereby it is free to move in an opposite direction.

A plate 35 is secured to the rudder arm 16 and catches 6 and 7 are pivoted to opposite ends thereof. A light spring 36 cooperates with each of the catches, whereby to press their inner ends outwardly. Dogs 8 and 9 are pivoted at their inner ends to the arm 16, and their outer ends are adapted to coact with the teeth 20 of the bar 19. The dogs 8 and 9 are mounted upon a stud or pin 37 carried by the arm 16. A trip 5 is pivotally mounted upon the element 37 and its outer end is connected to the dogs 8 and 9 by means of like contractile springs 38. The trip 5 controls the relative positions of the dogs 8 and 9 and the latter are reversed by the reversing of the trip 5, which is brought about by the action of the springs 38 in conjunction with the catches 6 and 7.

Trips 10 and 11 are pivoted at their outer ends to projections near opposite ends of the toothed bar 19 and their inner ends are disposed in the path of the outer end of the reversing trip 5. A contractile helical spring 39 cooperates with each of the trips 10 and 11, these springs 39 having connection at their inner ends with the respective clips 10 and 11 and being connected at their outer ends to projections of the toothed bar 19. When the rudder arm 16 is at the limit of its movement to the left, as indicated in Figure 1, the inner end of the trip 10 is in contact with the outer end of the trip 5 and the spring 39 is under tension. The trip 5 is held in the position indicated by the inner end of the catch 6 engaging a stop shoulder thereof at one end of a notch 40 formed in an edge of the trip. The dog 8 is in engagement with a tooth 20 of the bar 19, thereby holding the rudder arm 16 at the extreme movement to the left. With the parts in the position indicated in Figure 1, the windmill is out of the wind and consequently is inactive. Under these conditions, it is assumed that the tank 28 contains a

proper supply of water and the spring 24 has been stretched. As the water recedes in the tank 28 and the level thereof lowers, the float 27 descends and the connection 31 relaxing permits the spring 24 to come into play and move the trip bar 21 to the right and, as this movement takes place, the stop 13 approaches the outer end of the catch 6 and at the critical moment the catch 6 is tripped, thereby releasing the trip 5 which is reversed by a snap action by means of the trip 10 with the result that the dogs 8 and 9 are reversed, the dog 8 clearing the teeth 20 and the dog 9 engaging said teeth, whereby to prevent a reverse movement of the rudder arm 16 as the same is advanced or moved to the right by the action of the air current. The reverse position of the parts is indicated in Figure 3. As the rudder arm 16 moves relatively to the right, the dog 9 ratchets over the teeth 20 and holds the arm 16 in the advance position and prevents backward movement thereof. It will thus be understood that the windmill is gradually brought into action or into the wind by the variations in the air currents, thereby obviating the necessity of providing weights or springs usually employed for this purpose. When the rudder arm 16 reaches its extreme movement to the right, as indicated in Figure 2, the windmill is fully in the wind and operates to supply water to the tank 28 in a manner well understood. When the rudder arm 16 occupies the position indicated in Figure 2, the spring 39 cooperating with the trip 11 is under tension and exerts a pressure on the reversing trip 5 through the trip 11. As the float 27 rises in the tank 28, the connection 31 is drawn upon and moves the trip bar 21 to the left against the tension of the spring 24 and during this movement the stop 12 approaches the outer end of the catch 7 and at the critical moment the catch 7 is tripped, thereby releasing the trip 5, which is reversed by the action of the spring 39 coacting with the trip 11 and, as the trip 5 reverses, the dogs 8 and 9 likewise reverse, whereby to admit of movement of the rudder arm 16 to the left, whereby to throw the windmill out of the wind and action. The rudder arm 16 is provided with a bumper 41 which is double-ended to coact with each of the arms 17 and 18 to relieve the impact when the rudder arm reaches the limit of its movement in each direction.

What is claimed is:

1. In a windmill embodying a pivoted rudder arm, means for securing the rudder arm at the limit of its movement in each direction, a trip bar for effecting release of the rudder arm at either extreme position thereof, means normally holding the trip bar at the limit of its movement in one direction, and float operated means for effecting posi- 130

tive movement of the trip bar in a reverse direction.

2. In a windmill embodying a pivoted rudder arm, a ratchet mechanism for securing the rudder arm in either of its extreme positions and to prevent retrograde movement thereof when progressively advancing from one position to the other, a trip bar having a limited movement and adapted to reverse the ratchet mechanism, means normally holding the trip bar at the limit of its movement in one direction, and float operated means for moving the trip bar in a reverse direction.

15 3. In a windmill including a pivoted rudder arm, holding means for securing the rudder arm at the limit of its movement in each direction, means for reversing the holding means, a trip mechanism including a bar, 20 means normally holding said bar at the limit of its movement in one direction, and float operated means for reversing the movement of said bar.

4. In a windmill including a pivoted rudder arm, a toothed bar, oppositely disposed dogs carried by the rudder arm and adapted to cooperate with the toothed bar for securing the rudder arm in the required adjusted position, a reversing member for shifting the 30 position of the dogs, whereby to throw one into and the other out of action, clutches for holding the reversing member in adjusted position, spring actuated trip members adapted to exert a pressure on the reversing 35 member to effect positive movement thereof when released, whereby to reverse the said dogs, and a work-controlled trip member for effecting release of the reversing member.

5. In a windmill including a pivoted rudder arm, a toothed bar, opposed dogs carried by the rudder arm and in cooperative relation with said toothed bar, a reversing member for shifting the relative position of the dogs, opposed catches carried by the rudder arm and adapted to hold the reversing 45 member in the required adjusted position,

spring actuated trip members adapted to exert a pressure on said reversing member when the rudder arm is at the limit of its movement in each direction, and means for 50 tripping the catches, whereby to release said reversing member which is automatically operated by the spring actuated trip member in cooperative relation therewith.

6. In a windmill including a pivoted rudder arm, a toothed bar, opposed dogs carried by the rudder arm and in cooperative relation with said toothed bar, a reversing member, a yieldable connection between the reversing member and each of the said dogs, 55 opposed catches adapted to hold the reversing member in either one of its extreme positions, spring actuated trip members adapted to engage and cooperate with the reversing member, and means for automatically 60 tripping the said catches, whereby to release the reversing member which will effect a reversing of the dogs by the action of the trip member in cooperative relation with the reversing member.

7. In a windmill embodying a pivoted rudder arm, a toothed bar carried by the windmill head and having its toothed portion concentric with the axis of the rudder arm, opposed dogs carried by the rudder arm and adapted to cooperate with the toothed bar, a reversing member, yieldable connections between the reversing member and dogs, opposed catches for holding the reversing member in either one of its extreme positions, 80 spring actuated trips at opposite ends of the toothed bar, and a trip bar mounted upon the toothed bar and adapted to effect release of the catches to admit of reversing said dogs.

In testimony whereof I affix my signature in presence of two witnesses.

LUI C. VERGANO.
